[57] CLAIM

The ornamental design for a fitting for spas and the like, as shown.

DESCRIPTION

FIG. 1 is a perspective view taken from the top, front and right side of a fitting for spas and the like showing my new design;

FIG. 2 is a rear elevational view thereof;

FIG. 3 is a left side elevation view thereof; and

FIG. 4 is a bottom plan view thereof.

FIG. 1.FIG. 2.FIG. 3.FIG. 4.
